BOILER CLEANER

Application filed February 9, 1925, Serial No. 8,082. Renewed April 9, 1931.

The invention relates to boiler cleaners and has among its objects to provide blower means for discharging jets of cleaning fluid adjacent parts of the boiler to be cleaned. A further feature of the invention resides in novel means for controlling and operating a boiler cleaner in connection with a locomotive or other power plant.

Referring to the drawings:

Figure 1 is an elevation of a locomotive showing attached thereto feed water controlled means for actuating a boiler cleaner;

Figure 2 is a diagrammatic fragmentary horizontal sectional view through one of the side water legs of the locomotive showing the boiler cleaner in projected operative position;

Figure 3 is a detail view of the meter dial showing the control means for the boiler cleaner;

Figure 4 is an elevation partly in section showing the means for actuating the boiler cleaner;

Figure 5 is a section through 5—5 of Figure 4;

Figure 6 is a horizontal fragmentary section showing the retracting means for the blower;

Figure 7 is a view of a locomotive showing diagrammatically a modified form for operating a blower from a moving part of the locomotive.

Figure 8 is an elevation of the reduction gearing and valve control mechanism;

Figure 9 is a plan thereof;

Figure 10 is a plan view of a detail of a modified construction for actuating a plurality of blowers, and

Figure 11 is an elevation of the same showing the cleaning fluid supply pipes and valves therefor.

In the drawings reference character A indicates a locomotive of suitable construction, having the usual feed water line 10 including the meter B, the feed water line 10 leading to the usual injector or pump (not shown) for injecting the water into the boiler of the locomotive. The meter B may be of standard or other suitable construction fitted with the dials 11 as illustrated in Figure 3. One of

the dials is provided with a spring contact 12 rotatably mounted upon pin 13 and connected electrically with a lead 14. Mounted upon the meter in the path of the contact 12 are the posts 15, 16 and 17, the post 15 being neutral and the posts 16 and 17 each establishing one side of an electric circuit, by means of the lead wires 18 and 19 respectively; the other side of each of said circuits is completed, in turn, by contact of member 12 with the said posts 16 and 17. Member 12 is mounted on post 13, which is a moving part of the water meter, and is supplied with electrical energy thru the lead wire 14. The water in passing through the meter actuates the dial indicators and when a predetermined amount of water has passed through the meter the spring contact 12 bears against neutral post 15. As the meter contact is urged toward further revolution the tension of the spring contact will be increased until it is caused to snap past the neutral post 15 and engage the post 16 to establish an electrical circuit through leads 14 and 18. Likewise the spring contact will continue its engagement with post 16 until it snaps past this post and engages post 17 whereby an electrical circuit is established through leads 14 and 19. The purpose of the electric circuits will be presently apparent.

The locomotive A, as shown in Figure 2, is provided with the tube sheet 20, boiler tubes 21, and the side walls or water legs 22 one of which is shown in Figure 2. C indicates a boiler cleaner unit or blower element housed in a sleeve 23 extending through the water leg 22. Cleaning fluid from any suitable source may be supplied to the blower as by a pipe 26 fed by the main supply pipe 24, the supply of cleaning fluid to blower C being regulated by a solenoid valve 25. 27 is a branch supply pipe communicating with the main supply pipe 24 through a solenoid valve 28. The pipe 27 extends across the locomotive and communicates with the blower housed within the water leg on the opposite side. Solenoid valve 25 is connected with lead 19 and the valve 28 is connected with lead 18. The lead 14 extends to one terminal of a source of energy such as a dynamo or battery 29, the

other terminal thereof being connected by leads 30 and 31 with valves 25 and 28 respectively. Thus, each of the solenoids is included in an electric circuit controlled by the spring contact 12.

5 The pipes 26 and 27 supply cleaning fluid to the blowers C, one of which is preferably mounted in each of the side wall water legs 22 as aforesaid. Each blower is preferably constructed as shown in Figures 4, 5 and 6. The pipe 26 has a branch 32 terminating in a nozzle 33 for directing a jet of cleaning fluid against the blades of a turbine rotor 34 keyed to shaft 35, the latter being mounted in the 10 reduction gear housing D. 36 is a shaft upon which is mounted a gear 37 driven by the turbine rotor 34 through suitable reduction gearing E. The shaft 36 carries a worm 15 38 meshing with worm wheel 39 which is provided with a sleeved portion 40 having a splined connection with a shaft 41 by reason of the pin 42 engaging the slot 43 of the 20 shaft.

25 The cleaning fluid supply pipe 26 communicates with a chamber 44 of a fixed blower housing 45 mounted within the sleeve 23. This sleeve 23 may be expanded into the water leg of a locomotive boiler. The blower C comprises a slidable part 46 and a rotatable blower head 47, the part 46 having a pin 48 slidable in a slot 49 of the fixed housing. The part 46 also has a port 50 adapted to successively register, as the blower head 47 is rotated by shaft 41, with a plurality of 30 35 passages 51 each of which terminates in a nozzle 52. The nozzles are directed at different angles so that as they are successively brought to register with the port 50, cleaning fluid will be directed in successively advancing jets of cleaning fluid across the tube sheet of the locomotive for substantially half the width of the tube sheet, it being understood that where two blowers are used the blower on the opposite side will clean 40 45 the other half of the tube sheet.

50 Projecting from housing 45 are a plurality of guide pins 53 upon which is slidably mounted a plate 54 normally urged rearwardly by springs 55. The rear of shaft 41 is provided with a collar 56 pinned at 57 with the shaft 41. A thrust bearing 58 is provided for taking up the thrust produced by the cleaning fluid acting to project the blower C.

55 In operation of the parts, thus far described, the blowers C are normally housed within the respective sleeves 23 and thus protected from the heat of the fire chamber. The feed water in its passage through the feed water line 10 also passes through the 60 meter B to indicate in the customary manner the feed water consumption. The spring contact 12 is thus caused to periodically actuate the blowers successively, the period between operations being dependent upon the feed water consumption which affords a highly

desirable and efficient method of blowing. Thus as the contact 12 snaps off the neutral post 15, during the course of its revolution, it first contacts with the post 16 to establish a circuit through leads 14, 18 to actuate the 70 solenoid valve 28 whereby cleaning fluid from the main supply pipe 24 is conducted through the pipe 27 to the blower on the side opposite that shown in Figure 1. The period of automatic operation of the blowers is dependent 75 upon the steam consumption or rate of flow of the feed water and also the ratio between the movement of the contact 12 and the feed water flow. In a meter of usual construction the various indicators of the dials 11 move at 80 relatively differing speeds in proportion to a given flow of fluid through the meter and thus by selecting a suitable dial 11 for fitting the electric posts for the blower circuits, a cycle of any desired frequency of blowing 85 is afforded as well as a wide range of time intervals of actual blowing, the latter corresponding to the time of contact of the contact 12 with one of the posts 16 or 17. Thus after the contact 12 has actuated the blower 90 on the far side of the locomotive, as viewed in Figure 1, the contact 12 snaps past the post 16 to engage post 17 to establish a circuit through the leads 14, 19 so as to actuate the solenoid valve 25 to admit cleaning fluid from 95 the main supply pipe 24 to the pipe 26 leading to the blower shown in Figure 1. Simultaneously the circuit through leads 14, 18 is broken whereby the solenoid valve 28 closes to cut off the supply of steam to the blower connected with the pipe 27. It should be understood that the sequence of operation of the blowers is immaterial and that if desirable a single blower might be provided of such capacity as to clean the entire tube sheet and 100 other parts to be cleaned.

Upon actuation of the solenoid valve 25 to admit cleaning fluid from the main supply pipe 24 to the pipe 26, the blower is automatically projected forwardly under the influence of the cleaning fluid and against the action of the springs 55, into the position shown in Figure 5. Thus the blower head 47 and part 46 are projected forwardly the latter part guided by the engagement of the pin 48 with the slot 49. The rod 41 carrying the blower head is also projected forwardly toward the fire box, carrying also the plate 54 and compressing springs 55, the thrust bearing 58 absorbing the force of the thrust. The shaft 41 has splined engagement at 42, 43 with the worm wheel 39 whereby the worm wheel can actuate the shaft 41 in its projected position. Cleaning fluid supplied through pipe 26 passes through the chamber 44 and thence to the stationary port 50 for successively supplying cleaning fluid to the passages 51 as they are successively brought into registration with port 50 as will be presently apparent. 110 115 120 125 130

Simultaneously with the projecting of the blower, cleaning fluid passing through pipe 26 and branch pipe 32 is ejected from nozzle 33 to act upon the turbine 34 to cause rotation of shaft 35. The latter shaft, through the reduction gearing E, serves to rotate the shaft 36 carrying the worm 38 which in turn actuates shaft 41 to rotate the blower head 47 relatively to the part 46. Thus cleaning fluid is successively supplied to the nozzles 52 which, by reason of their varying angularity, cause jets of cleaning fluid to sweep the tube sheet so as to trace lines across the tube sheet advancing to substantially midway of the tube sheet, where two blowers are employed. By proportioning the relative circumferential length of the port 50 and passages 51 the cleaning fluid may be admitted and cut off at the desired points so as to restrict the jets 20 of cleaning fluid to the parts of the boiler to be cleaned. Upon breaking of the circuit through leads 14, 19, the solenoid valve 25 acts to cut off the supply of cleaning fluid to the pipe 26, the springs 55 acting on plate 25 54 and shaft 41 to return the blower within the sleeve 23.

The blowers will then remain inoperative until a predetermined amount of water has been supplied to the boiler so as to cause another revolution of the spring contact 12 to again repeat the cycle described above.

Instead of causing the blowers to be automatically actuated after passage of a predetermined amount of feed water to the boiler by a movable member 12 responsive to the flow of feed water, such automatic control of the blowers might be effected from other moving parts of the power plant. As a further illustration, of our invention the following mechanism may be provided.

Referring to Figure 7 the locomotive A' may be equipped with a blower C', reduction gear housing D which includes the turbine and reduction mechanism for actuating the blower, cleaning fluid supply pipe 26', and branch 32', all of which parts may be similarly constructed as the corresponding parts described above.

Suitably supported or suspended as by brackets 60 from a convenient part of the locomotive as the running board 59 is a gear box F, which contains a gear 61 mounted on a shaft 62. 63 indicates a shaft carrying a disc 64, the shaft 63 being actuated from the gear 61 through a suitable train of reduction gears G. Upon the disc 64 is a cam 65 in the path of which is a valve stem 66 carrying a valve disc 67. The valve disc 67 controls the passage of cleaning fluid from a main supply pipe 68, connected with a suitable source of cleaning fluid such as the steam dome 69, to the supply pipe 26'. H indicates the fitting which encloses the valve 67 and connects the pipes 68 and 26'. A spring 70 normally holds the valve 67 upon its seat 71 to prevent

the passage of cleaning fluid from the main supply pipe 68 to the pipe 26'. 72 is a rocker arm which may be rockingly supported at 73 from a convenient part of the locomotive. Connected at 74 with the rocker arm 72 is a dog 75 which engages the teeth on gear 61 to actuate the same. The rocker arm may be rocked by connecting it with any suitable movable part of the locomotive as, for example, the rocker arm may be connected at 75 with the main locomotive valve actuating mechanism J.

If preferred, a blower C' may be located on either side of the locomotive, the mechanism shown in Figure 7 being duplicated on the other side; or if preferred, a single blower may be employed of suitable capacity for cleaning all of the parts desired; or a blower may be located in each of the side wall water legs of the locomotive, both blowers being controlled by mechanism on only one side of the locomotive. To the latter end the mechanism as described above may be modified as shown in Figures 10 and 11. In these views the disc 64' is formed with a pair of cams 65^a and 65^b which rotate in separate planes and are adapted to successively engage the valve stems 66^a and 66^b of the fittings H^a and H^b respectively to unseat the valves 67^a and 67^b. The valve 67^a, upon being unseated by contact of the cam 65^a with the valve stem 66^a, admits cleaning fluid from the supply pipe 68' to the pipe 26^a which supplies cleaning fluid to one of the blowers on one side of the locomotive. The disc 64' may be actuated in a manner corresponding to the mechanism described for operating the disc 64 and the blowers may also be similar to that shown in Figures 4, 5 and 6. As the disc 64' rotates, the cam 65^a will pass beyond the valve stem 66^a to permit the valve 67^a to be seated under the influence of spring 70^a, thus shutting off the supply of cleaning fluid from the supply pipe 68' to the pipe 26^a. The cam 65^b will then actuate the valve stem 66^b to unseat the valve 67^b against the action of spring 70^b, thus establishing communication between the supply pipe 68' and the pipe 26^b leading to the blower on the side of the locomotive opposite to that communicating with the pipe 26^a.

By arranging suitable gearing at G, one revolution of the disc 64 or 64' may be made to correspond to any number of miles of travel of the locomotive so that the tube sheet, tubes and other parts of the boiler can be cleaned every time the locomotive travels a predetermined distance. The cams 65, or 65^a and 65^b, may be suitably shaped to give the performance of the blowers as desired. For example by increasing or decreasing the circumferential face of the cams, the period of blowing may be increased or decreased. The valve stems 66, or 66^a and 66^b, will be actuated slowly or quickly depending on how steep the 130

radial faces of the respective cams are, as will be readily understood.

In operation, after a predetermined distance has been travelled by the locomotive, 5 the rocker arm 72 will have actuated the dog 75 and gear 61 so that the disc 64 will have been rotated sufficiently to cause the cam 65 to act upon the valve stem 66 to unseat the valve 67 as shown in Figure 8, thus supplying cleaning fluid from the main supply pipe 68 to the pipe 26' and thence to the blower such as shown in Figures 4, 5 and 6. As the disc 64 continues to slowly rotate, the cam 65 will be carried beyond the point of engagement of 10 the cam and valve stem 66, whereupon the spring 70 will return the valve 67 to its seat and cause the blower to be retracted to its inoperative position. Likewise, the blower on the opposite side of the locomotive will function 15 in any predetermined time relation every time the locomotive has travelled a predetermined distance.

In the modification shown in Figures 10 and 11, in which the actuating mechanism for the 20 blowers is entirely located on one side of the locomotive, the disc 64' first actuates one of the valve stems, as 66 by contact with the cam 65^a, and preferably after the blower communicating with pipe 26^a has functioned, the cam 25 65^b acts to unseat valve 67^b to cause the other blower connected with the pipe 26^b to function.

While we have shown our invention applied to locomotive power plants it should be 30 understood that the invention is in no manner confined thereto, as the performance of blowers used in connection with stationary power plants may be likewise caused to automatically function after a predetermined consumption 35 of feed water which corresponds to a predetermined generation of steam or after a predetermined movement of any convenient moving part associated with the power plant. Furthermore, instead of employing blower 40 units of the construction shown in Figures 4, 5 and 6, it is obvious that any other suitable construction of blower unit might be substituted therefor. For example, instead of employing a blower having a rotatable blower 45 head as shown in Figure 5, a blower oscillated by suitable mechanism might be employed, or a non-rotating, non-retracting or non-oscillating blower might also be employed in which latter instance the mechanisms provided by 50 our invention might serve to automatically admit cleaning fluid to such blowers at predetermined intervals. Also, if desired, both of the blowers described, or any number of blowers could be operated simultaneously or 55 in any sequence preferred.

What we claim as our invention is:—

1. In combination with a boiler including a feed water supply therefor, a boiler cleaner unit, a supply of cleaning fluid, and means 60 controlled by the feed water supply for ad-

mitting cleaning fluid from said cleaning fluid supply to said unit.

2. The combination with a boiler, of a cleaner unit therefor, and means controlled by the quantity of feed water supplied to the 70 boiler for operating the cleaner unit.

3. The combination with a boiler, of a cleaner unit therefor, and means controlled by the quantity of feed water supplied to the 75 boiler for periodically operating the cleaner unit.

4. The combination with a locomotive provided with a feed water supply pipe, of a blower unit for cleaning parts of the locomotive boiler, means for actuating said blower 80 unit, and means actuated by the flow of feed water in said supply pipe for periodically and automatically setting the first mentioned means into operation.

5. The combination with a locomotive provided with a feed water supply pipe, of a blower unit for cleaning parts of the locomotive boiler, means for actuating said blower unit, and means controlled by the flow of feed water in said supply pipe for setting said first 90 mentioned means into operation.

6. The combination with a boiler provided with a feed water supply pipe, of a projectable and retractable blower unit for cleaning parts of the boiler and feed water 95 controlled means for controlling the projection of said blower into cleaning position.

7. The combination with a boiler provided with a feed water supply pipe, of a projectable and retractable blower unit for cleaning parts of the boiler and feed water 100 controlled means for effecting projection of said blower into cleaning position, and a spring associated with the blower for there- 105 after retracting the blower.

8. The combination with a boiler provided with a feed water supply pipe, of a projectable blower unit normally housed within a wall of the boiler, a supply of cleaning fluid, and 110 feed water controlled means for controlling the admission of cleaning fluid to said blower and for thereby controlling the projection of the blower.

9. In combination with a boiler provided with a feed water supply pipe, a boiler cleaner unit therefor, a supply of cleaning fluid for said unit, a valve controlling the passage of cleaning fluid from said supply to said unit, and feed water controlled means 115 for periodically operating the valve dependent upon the passage of a predetermined amount of feed water through said feed water supply pipe.

10. In combination with a boiler provided with a feed water supply pipe, a boiler cleaner unit, a supply of cleaning fluid for said unit, a solenoid valve controlling the passage of cleaning fluid from said supply to said unit, means operable 120

- upon the passage of a predetermined amount of water through the said supply pipe for periodically establishing an electric circuit for operating the solenoid valve.
- 5 11. In combination with a boiler provided with a feed water supply pipe, a rotatable blower unit, a supply of cleaning fluid, and feed water controlled means for admitting cleaning fluid from said supply to said blower and for effecting the rotation of said blower. 70
- 10 12. In combination with a boiler provided with a feed water supply pipe, a rotatable and projectable blower unit, a valve controlled source of cleaning fluid for said blower unit, and means controlled by said feed water for opening the valve for admitting cleaning fluid to the blower and for thereby effecting the projection and rotation of said blower. 75
- 15 13. In combination with a boiler provided with a water supply pipe, a boiler cleaner unit, a supply of cleaning fluid, a prime mover for moving the said unit, and feed water controlled means for admitting cleaning fluid to said unit for cleaning parts of the boiler and for effecting the operation of the prime mover. 80
- 20 14. In combination with a boiler provided with a feed water supply pipe, a movable boiler cleaner unit, a supply of cleaning fluid, a fluid operated prime mover geared with the cleaner unit for moving the same, and feed water controlled means for conducting cleaning fluid to said unit for cleaning parts of the boiler and to said prime mover whereby the prime mover is actuated to move the boiler cleaner unit. 85
- 25 15. In combination with a locomotive boiler having a tube sheet, side wall water legs and a feed water supply pipe, a source of cleaning fluid, a projectable and rotatable blower unit normally housed within each water leg for directing a jet of cleaning fluid again the locomotive tube sheet, means operated by the cleaning fluid for projecting each blower, means operated by the cleaning fluid for rotating each blower, and feed water controlled means periodically and automatically 90
- 30 acting upon passage of a predetermined amount of feed water through said supply pipe for successively supplying cleaning fluid to the blowers from said source of cleaning fluid and for thereby successively effecting the rotation and projection of said blowers. 95
- 35 16. In combination with a boiler including a feed water supply therefor, a plurality of boiler cleaner units for cleaning parts of the boiler, a source of cleaning fluid, and feed water controlled means for supplying cleaning fluid to said blowers. 100
- 40 17. In combination with a boiler including a feed water supply pipe therefor, a plurality of boiler cleaner units for cleaning parts of the boiler, a valve controlled source 105
- 45 of cleaning fluid for the units, means for actuating said valve, and means controlled by the passage of feed water through said supply pipe for setting said first mentioned means into operation. 110
- 50 18. The method of cleaning boilers consisting in providing a supply of cleaning fluid, passing feed water to the boiler, and blowing the cleaning fluid adjacent parts of the boiler to be cleaned periodically depending on a predetermined quantity of feed water supplied to the boiler. 115
- 55 19. The method of operating and cleaning a boiler consisting in supplying the boiler with feed water and cleaning those surfaces of the boiler exposed to the products of combustion periodically after a predetermined quantity of feed water has been supplied to the boiler. 120
- 60 20. The combination with a locomotive having a boiler, of a fluid conduit communicating with the boiler, the amount of fluid passing through said conduit being in dependence upon the rate of boiler operation, a member movable in timed relation to the passage of fluid through said conduit, a boiler cleaner unit, and means actuated by the said movable member for automatically controlling the operation of the said boiler cleaner unit. 125
- 65 21. The combination with a locomotive boiler having a tube sheet, a feed water supply pipe, and a plurality of blower units for discharging cleaning fluid toward said tube sheet, of means operable in dependence upon the flow of feed water through said supply pipe for periodically and successively actuating the said blower units. 130
- 70 22. The method of cleaning those surfaces of a boiler which are exposed to the products of combustion which consists in effecting a removal of the deposits from said surfaces periodically in dependence upon the supply of predetermined quantities of feed water to said boiler. 135
- 75 23. The combination with a boiler and a fluid conduit communicating with the boiler, the amount of fluid passing through said conduit being in dependence on the rate of boiler operation, of a cleaner unit for the boiler, and means operable in dependence upon the flow of fluid through said conduit for controlling the operation of said cleaner unit. 140
- 80 24. The method of cleaning a boiler which consists in periodically discharging cleaning fluid adjacent the portions of the boiler to be cleaned in dependence upon the quantity of feed water supplied to the boiler. 145
- 85 25. The combination with a boiler, of a plurality of cleaner units therefor, and means controlled by the quantity of feed water supplied to the boiler for successively operating the said cleaner units. 150
- 90 26. The combination with a boiler, of a cleaner unit therefor, and means controlled 155

by the quantity of feed water supplied to the boiler for operating the cleaner unit, said means including a contact arm movable into and out of engagement with a stationary contact in dependence upon the quantity of feed water supplied to the boiler.

27. The combination with a boiler, of a cleaner unit therefor, and means controlled by the quantity of feed water supplied to the boiler for controlling the operation of the cleaner unit, said means including a meter having a shaft movable in timed relation to the flow of feed water to the boiler, and a contact member movable by said shaft.

28. The combination with a boiler, of a cleaner unit therefor, and means controlled by the quantity of feed water supplied to the boiler for controlling the operation of the said cleaner unit, said means including a pin 20 rotatable in timed relation to the flow of feed water to the boiler, a stationary contact, and a resilient contact carried by said pin and movable into and out of engagement with said stationary contact, the resiliency of said second mentioned contact providing for engagement of said contact with the stationary contact during a portion of the rotation of said pin.

29. The combination with a boiler, of a casing having a cleaning fluid inlet and a supply port, a projectable blower journaled in said casing having a plurality of ports adapted to be successively placed in communication with said supply port upon relative movement of the blower and casing, and means controlled by the quantity of feed water supplied to the boiler for effecting a relative movement of the blower and casing whereby said successive communication is effected.

30. The combination with a boiler, of a casing provided with a cleaning fluid inlet and cleaning fluid supply passage, a blower member rotatably mounted in said casing and provided with a plurality of nozzles adapted to be placed in communication successively with the cleaning fluid supply passage in said casing upon rotation of the blower member, and means controlled by the quantity of feed water supplied to the boiler for effecting a rotation of said blower member relative to said casing.

In testimony whereof we affix our signatures.
